UNITED STATES PATENT OFFICE.

VENA A. MILLER, OF BLOOMDALE, OHIO, ASSIGNOR OF ONE-FOURTH TO MERLE REARICK AND ONE-FOURTH TO CARL W. BROWN, OF BLOOMDALE, OHIO.

ANTICREEPER.

1,169,051.

Specification of Letters Patent. Patented Jan. 18, 1916.

Application filed June 1, 1914. Serial No. 842,299.

To all whom it may concern:

Be it known that I, VENA A. MILLER, a citizen of the United States, residing at Bloomdale, in the county of Wood, State of Ohio, have invented certain new and useful Improvements in Anticreepers; and I do hereby declare the following to be a full, clear, and exact description of the invention, such as will enable others skilled in the art 10 to which it appertains to make and use the same.

This invention relates to improvements in attachments for railway rails, and particularly to attachments for preventing creeping 15 of the rails.

The principal object of the invention is to provide a device for preventing the creeping of railway rails which can be effectively locked in position.

20 Other objects and advantages will be apparent from the following description, when taken in connection with the accompanying drawings.

In the drawings: Figure 1 is an elevation 25 of my device in position, the railway rail being shown in section. Fig. 2 is a vertical sectional view through the device on a line transversely of the rail. Fig. 3 is a vertical sectional view on the line 3—3 of Fig. 1. 30 Fig. 4 is a perspective view of the locking key or wedge.

It is a well known fact that the tendency 35 of railway rails to creep is particularly noticeable on double track lines where the trains all run in one direction and is especially troublesome on grades. The attempts usually made to overcome this movement consists chiefly in applying a clamp to the foot flange of the rail, the clamp being 40 provided with a foot to abut against the adjacent tie, so that when the rail tends to creep, the tie receives the pressure through the foot. Various objections are made to this form of anti-creeper, chief among which 45 is that the jaws of the clamp soon relax, thereby allowing the rail to creep as before.

To overcome these objections is the principal object of my invention.

Referring particularly to the accompany-

ing drawings, 10 represents the shank or 50 stem of the device which is disposed transversely under the base of the rail 11 and adjacent the tie. At one end of the stem or shank is formed a head 13 which is approximately in the shape of a hook and engages 55 with one edge of the basal flange of the rail. A series of corrugations or teeth 14 are formed within the hook for biting engagement with the edge of the base of the rail. At the opposite end of the shank is an en- 60 larged head 15 formed with a downwardly extending weighted brace. The upper portion of the member 15 is formed with an inwardly directed hook 17 resulting in a transverse recess 18. Arranged to slide 65 transversely through this recess is a wedge block or key 19, one side of which is formed with a longitudinal channel 20, in the bottom of which there are formed the serrations 21. This channel receives the opposite side 70 of the base of the rail, and as the wedge key is driven through the recess these teeth bite into the rail and force the same tightly into the hook 13. On the smaller end of the key is a finger or lip 22 which is adapted to be 75 bent upwardly after the key is driven in so as to engage against one side of the hook 17 and prevent loosening or removal of the key. It will be noted that the channel side of the key is parallel with the edge of the rail and 80 that the serrated bottom wall of the channel bears against this edge of the base of the rail at all points, while the opposite side of the key inclines toward the lip 22, and engages a correspondingly inclined face in the 85 hook 17.

What is claimed is:

An anti-creeping device comprising a shank disposed transversely beneath the basal flange of a rail, a flange engaging hook 90 member carried by one end of the shank, a larger hook member carried by the opposite end of the shank for the reception of the opposite side of the basal flange, a channeled wedge key disposed between the larger hook 95 and the basal flange and receiving the said flange in the channel, the smaller hook member and the channel of the key being formed

with teeth for biting engagement with the edge faces of the basal flange of the rail, and a lip formed on the smaller end of the wedge key bent at right angles to the key and 5 against one side face of the larger hook member.

In testimony whereof, I affix my signature, in the presence of two witnesses.

VENA A. MILLER.
